MEANS FOR HANDLING DROP BOTTOM CONTAINERS

Graham C. Woodruff, Bronxville, N. Y., assignor to The L. C. L. Corporation, a corporation of Delaware

Application October 5, 1936, Serial No. 104,095

2. Claims. (Cl. 212—11)

This invention relates to novel and improved means for handling drop bottom containers, such as drop bottom containers adapted for transportation on container cars, and particularly to drop bottom containers of that type designed to be raised, lowered and moved from point to point by the action of a crane which also serves to control the action of the container drop doors.

The means ordinarily employed in connection with crane mechanisms for handling such containers in a satisfactory manner requires the use of double lines, one to raise and lower the container and the other to control the doors. It is, however, desirable in many kinds of work, where single line cranes are employed, as, for example in handling open hearth furnace commodities, to provide a means whereby all operations of raising, lowering and moving the containers from point to point, and including the work of controlling the actions of the doors, may be performed by the single line of a single line crane, such as a Gantry drum crane, commonly used as part of the equipment in many open hearth furnace plants.

One object of my invention is to provide a handling means for use in connection with a single line crane and a drop door type of lift container whereby all the operations specified may be performed by manipulation of the single line of such a crane.

Another object of the invention is to provide a handling means of the character set forth which is of simple construction and may be used in connection with a lift type container of general service type without modification of the container structure per se.

With these and other objects in view, the invention consists of the features of construction, combination and arrangement of parts, herein after fully described and claimed, reference being had to the accompanying drawings, in which:—

Fig. 1 is a view in end elevation of a container held suspended by my improved handling means from a single line crane in position for transport thereby to or from a container car, a container car of conventional type being shown.

Fig. 2 is a side elevation of the suspended container and coacting parts of the handling means shown in Fig. 1.

Fig. 3 is an end elevation of the container as lowered by the crane to dumping position.

Fig. 4 is a view partly in section and partly in end elevation of a construction of container in

connection with which my improved handling means may be employed.

Fig. 5 is a view partly in section and partly in side elevation of the container shown in Fig. 4.

Referring now more particularly to the drawings, 1 designates a container of the type described which may be of rectangular, oblong rectangular or other suitable form. This container is fully open or provided with a filling opening at its top for introduction of the lading, which opening may be closed or not by a suitable door or doors. The container is open at its bottom for discharge of the lading and is provided with hinged drop doors 2 for holding the lading confined until it is desired to dump it and then dumping the same. Chains or cables 3 are attached to these doors and pass upwardly through guide housings 4 to the top of the container, where their upper free ends are provided with attaching eyes 5 or the like. At the corners of the container at its top are provided lifting links 6. In the respects noted the container may accord in construction with that disclosed in my copending application for patent Serial No. 28,742, filed June 27, 1935, or be of any equivalent or suitable construction. The housings 4 may be arranged either on the inside of the container or on the outside as shown.

1 designates an overhead traveling crane of the general type described, that is, one having a single suspending and control line 8 controlled in operation by the crane line winding and unwinding mechanism. This line depends from and is movable with the crane carriage mounted on the traveling crane bridge, and means, in accordance with my invention, are provided for raising and lowering the container, moving the suspended container from point to point, and controlling the action of the drop doors of the container, from this line.

This means comprises a sling for controlling the drop door operating chains or cables 3, and for raising, lowering and shifting the container, and a sling for supporting the container when in dumping position. The first mentioned sling, as shown, is in the form of a spreader bar 9 which is fastened to the crane line 8 and from which depend lines 10 provided at their lower or free ends with safety latch hooks 11 for engagement with the eyes 5 of the door operating cables 3. The container supporting sling, as shown, comprises a spreader bar or plate 12 connected with the crane carriage by dead lines 13 and carrying a safety latch hook 14 for connection to the eye 15 of a conventional type four-branch cable sling 55

16, the lower or free ends of which are provided with safety hooks 17 for engagement with the lifting links 6 at the corners of the container. The lines 13 are of such length as to act as a limitation means to limit the lowering of the container with respect to the level of the crane and to the ground or floor line and to stop the downward movement of the container at and to prevent it from descending below a predetermined dumping level. The lines 3 and 8 are not so limited in their downward movement, however, and through their action the opening and closing movements of the doors may be effected when the container is in dumping position.

15 The operation is as follows:

Assuming that a material for use in an open hearth furnace plant has been shipped in containers of the character described placed in a container car, such a car, indicated at 18, being shown in Fig. 1, it will be understood that when the loaded containers are placed on the car and rested on the floor thereof the weight of each container serves to hold its drop doors, which lie in contact with the car floor, in closed condition against escape of its lading, without the use of fastening means for holding the doors in such condition. Releasable fastening means for holding the doors closed may, however, be employed. Assuming also that the individual containers are to be removed from the car and transported to some certain point or to different points in the plant and dumped, the crane 7 is employed for this purpose. To this end the crane 7 with the slings applied thereto is brought into position so that the hooks of the slings may be engaged with the eyes of the door operating cables and lifting links of one of the containers, the crane line 8 being suitably lowered to allow this to be done, the dead lines being of sufficient length to permit the engagement of the safety hooks with the container lifting links 6. The crane line 8 is then raised to lift the engaged container from the car 18. In this operation of lifting the container to the necessary height to clear the car 45 and raise the container to transport level, the sling lines 10 connected with the spreader bar 9 on the initial part of the upward movement of line 8 will draw upon the cables 10 to draw the cables 3 taut, thus holding the doors 2 closed against the weight and escape of the lading and forming therethrough a lifting connection between the line 8 and the container 1, whereby as the upward movement of the line 8 continues the container will be lifted from the car to the elevated transport position shown by the suspended container in Fig. 1. This upward movement of the line 8 results in the slackening of the cables 13 and 16 which are inactive for container suspending purposes so long as the container is suspended from the crane by the line 8 at this transport level. The suspended container may then be transported by the crane 7 to the point at which the lading is to be dumped, for example at a point for use in proximity to an open hearth furnace front, as shown in Fig. 3. To effect the dumping of the lading the line 8 is then lowered to a level at which the limitation cables or dead lines 13 and the sling cables 16 are straightened out or rendered taut, where- 70 by the support of the container is transferred to these cables, thus holding the container from further downward movement so that under a continued downward movement of the line 8 the cables 3 will be free for downward movement in 75 their housings under the weight of the doors and

the lading resting therein. The doors will thus be allowed to open for the discharge of the lading as shown in Fig. 3. On the discharge of the lading, the line 8 and the cables 3 are again drawn upward, closing the doors, and resulting in 5 an upward movement of the container after the drop doors have closed. This upward movement of the line 8 is continued until the container is raised to transport position, during which the cables 13 and 16 are restored to an inactive and 10 slack condition and the support of the container again fully transferred to line 8 and cables 3 so that the empty container may be transported back to the container car from which it has been removed or to another container car or other 15 point where it may be loaded, if desired, with a commodity which is to be shipped from the plant.

From the foregoing description, taken in connection with the drawings, the construction and mode of operation of my improved means for the 20 crane handling of drop bottom containers will be readily understood, and it will be seen that the invention provides a simple, reliable and efficient means whereby a container may be raised, lowered and transported and its doors controlled 25 in operation by the single draft line of a single line crane, such as one of the character referred to, allowing ready handling of such containers in establishments equipped with such cranes without changing the construction of the 30 container, which may also be handled in the ordinary way by two line cranes. While the construction of the means shown herein by way of exemplification for carrying the invention into practical effect is preferred, it is of course to be 35 understood that changes in the form, construction and arrangement of the parts may be made within the scope of the appended claims, without departing from the spirit or sacrificing any of the advantages of the invention. 40

What I claim is:—

1. Hoisting means for use with a traveling crane carriage having a single draft line, and a container having a body provided with lifting links at the corners thereof, a drop bottom and operating lines connected with said drop bottom, said hoisting means comprising a sling consisting of a spreader, flexible dead lines connecting said spreader on opposite sides of its center with the frame of the crane carriage, and sustaining 45 lines connecting said spreader with the lifting links of the container, said dead and sustaining lines being of fixed length rendered taut when the container is lowered to dumping position to support the container and to be slackened when the 50 container is raised above such position to a higher transport position and thereby rendered ineffective to support the container, and a second sling comprising a spreader arranged at right angles to the first-named spreader and connected with the draft line, and flexible lines connecting said spreader with the drop door operating 55 lines of the container for raising and lowering the container between such dumping position and higher transport position and operating 60 the drop doors when the container is supported in dumping position by the first-named sling. 65

2. Hoisting means for use with a traveling crane bridge, a traveling crane carriage thereon having a single draft line, and a container having a body, lifting links at the corners of said body, a drop bottom, and operating lines connected at their lower ends with said drop bottom and provided at their upper ends with coupling eyes, said hoisting means comprising a 75

sling consisting of a spreader of inverted triangular form, flexible dead lines connecting said spreader on opposite sides of its center with the frame of the crane carriage, sustaining lines connected with the lifting links of the container, and a two-part detachable link connection between said sustaining line and the vertex portion of said spreader, said dead and sustaining lines being of fixed length so as to be rendered taut 5 when the container is lowered to dumping position to support the container and to be slackened when the container is raised above such position to a higher transport position and there-

by rendered ineffective to support the container, and a second sling comprising a spreader arranged at right angles to the first-named spreader and connected with the draft line, and flexible lines connecting said spreader with the eyes of the drop door operating lines for raising and lowering the container between said dumping position and higher transport position and operating the drop doors when the container is supported in dumping position by the first-named 10 sling. 5

GRAHAM C. WOODRUFF.
